UNITED STATES PATENT OFFICE

2,000,172

HINGE

Walter M. Hanson, Grand Rapids, Mich., assignor to American Seating Company, Grand Rapids, Mich., a corporation of New Jersey

Application October 23, 1933, Serial No. 694,748

4 Claims. (Cl. 155—86)

The present invention relates to hinges and more particularly to an improved seat hinge of the general character illustrated and described in United States Letters Patent No. 5 1,810,888, issued June 16, 1931, to my assignee on application filed by me November 3, 1930, Serial No. 492,940.

The main objects of the invention are to provide a seat hinge for use in conjunction with seats such as opera chairs and the like; to provide a seat hinge which is adjustable with respect to arcuate seating; to provide a seat hinge of the character above indicated which is capable of ready and convenient assembly; and, to 10 provide a seat hinge assembly many parts of which are of stamped sheet metal with its consequent economical cost of manufacture.

An illustrative embodiment of the invention is shown in the accompanying drawings, where- 15 in:

Figure 1 is a vertical sectional view of a chair of the opera type such as is used in conjunction with public seating, a portion of the seat being broken away and showing the seat hinge assembly;

Figure 2 is an enlarged fragmentary view of the seat hinge assembly per se, partly in section and partly broken away;

Figure 3 is a perspective view of one of a pair of cupped plates which with its companion cupped plate shown in Figure 5 are adapted to rotatably embrace the truncated spherical element shown in Figure 4;

Figure 4 is a perspective view of the truncated spherical element per se referred to in connection with the description of the member illustrated in Figure 3;

Figure 5 is a perspective view of the companion cupped plate illustrated in Figure 3;

Figure 6 is an enlarged fragmentary sectional view of the seat hinge assembly on line 6—6 of Figure 7;

Figure 7 is a sectional view thereof on line 7—7 of Figure 6; and

Figure 8 is a sectional view on line 8—8 of Figure 6.

Referring to the drawings in which like parts of the structure are designated by the same numerals in the several views, the construction herein illustrated comprises the supporting member 1 or seat standard with its supporting legs 2, arm rest 3 and upholstered back 4.

This supporting standard, preferably of cast metal, is here shown as provided with a pair of cups disposed on its opposite sides and de-

fined by the laterally projecting walls 5 of oval shape as best shown in Figure 6. These oppositely disposed cups together with the apertured plates 6, each secured adjacent the rim of its respective cup as by the screws 7, form a housing for the seat hinge assembly. Within each cup on the opposite sides of the supporting standard and substantially centrally thereof is a laterally projecting boss 8 provided with a horizontally disposed aperture 9.

A pair of spherical elements 10 whose opposite sides are parallelly truncated, are each provided with a rivet receiving aperture 11 disposed transversely with respect to the parallel plane surfaces of the spherical element and a pair of identically formed flat plates 12, preferably of stamped sheet metal, each having a cupped portion 13 as best shown in Figures 3 and 5, rotatably embrace each spherical element on its opposite sides and are secured together adjacent their flat surfaces as by spot welding. The cupped portion of these plates are provided with a rivet receiving aperture 14 permitting the rivet 15 to pass therethrough for securing the spherical elements on opposite sides of the supporting standard with one plane surface of each spherical element in juxtaposition with the plane surface of the bosses 8 as best shown in Figure 7.

A squared tubular shaft 16 has a pair of spaced lugs 17 projecting from one end thereof and through the flat surfaces of the cupped plates 12, the ends thereof being flattened to secure the shaft axially therewith about the cupped portion thereof. The outer end of the shaft is provided with a pair of registering slotted openings 18 and a stamped seat supporting bracket 19 for supporting the seat 20 is provided with a laterally projecting U-shaped stamped arm 21 embracing the shaft 16 and laterally adjustably secured thereto by the bolt 22 passing therethrough and through the slotted openings 18 as best illustrated in Figure 7.

Pairs of oppositely disposed spaced stops 23, 24 of rubber or the like are secured within the seat hinge housing as best seen in Figure 6 for alternately engaging the flanged sides 25 of the plates 12 during the rotating movement of the plates upon their respective spherical elements 10 as indicated by the arrows in Figure 6. The weight of the person occupying the seat is thus supported by the stops 23, 24 rather than by the rivet 15.

Because of the rotatable connection between the flat plates 12 and their respective spherical

elements 10 as herein before described, a limited universal joint movement is permitted between them and the seat hinge is thus adaptable for arcuate seating. It will thus be seen that the 5 seat hinge is capable of ready and convenient assembly and that many parts of the seat hinge assembly are of stamped sheet metal making for economy in manufacture.

10 While but one specific embodiment of this invention has been herein shown and described, it will be understood that numerous details of the construction shown may be altered or omitted without departing from the spirit of this invention as defined by the following claims.

15 I claim:

1. In a structure of the class described, a supporting member having a plane surface provided with a rivet receiving aperture, a solid spherical element whose opposite sides are parallelly 20 truncated to form flat side faces and provided with a rivet receiving aperture disposed transversely with respect to the parallel plane surfaces of the spherical element, a pair of flat plates each having a cupped portion provided 25 with an aperture therein for permitting the passage of a rivet and rotatably embracing the spherical element on its opposite sides and whose flat surfaces are secured to each other, and a rivet passing through said apertures and extending 30 entirely through the spherical element and engaging the side face thereof remote from the supporting member for securing the spherical element to the supporting member with one of the plane surfaces of the spherical element in 35 juxtaposition to the plane surface of the supporting element to thereby form a semi-universal joint between the spherical element and said plates.

2. In a structure of the class described, a middle seat supporting standard, identical elements 40 secured to opposite sides of the standard and having spherical surfaces, a pair of members for each of said spherical elements, each member of said pair having a cupped portion rotatably embracing the spherical surface of its respective element and the member of said pair secured to each other in their respective assembled relations with their spherical element, hollow shafts 45 extending from each pair of said members and connected therewith, pivots carried by said hollow shafts and disposed perpendicular to the

axis of rotation of said members in spaced relation thereto, and seat brackets connected to the said pivots.

3. In a structure of the class described, a supporting member provided with laterally projecting walls of approximately oval formation and having a rivet receiving aperture within the space enclosed by the said walls, a plate secured to the walls and co-operating therewith to form a housing and having a central opening, a solid 10 truncated spherical element having flat side faces and provided with a rivet receiving aperture disposed transversely with respect to the said side faces, said spherical element being located within the said housing with one of its 15 side faces fitted against the supporting member, a rivet passing through the said apertures and extending entirely through the spherical element for securing the same to the supporting member and engaging the side face of the spherical element remote from the supporting member, a pair of flat plates located within the said housing and each having a cup-shaped portion rotatably embracing the spherical element on opposite sides thereof, an axially disposed shaft 20 connected with the said plates and extending through the opening of the housing, a pivot arranged exteriorly of the said housing and mounted on and carried by the said shaft and disposed perpendicular to the axis of the said 25 pair of plates, and a seat supporting bracket 30 connected with the said pivot.

4. In a structure of the class described, a supporting member, an element secured to the supporting member and having a spherical surface, a pair of cupped members rotatably embracing said element and provided at their ends with extensions fitted flat against each other and having laterally extending flanges forming abutment surfaces, a hollow shaft provided with lugs 40 piercing the extensions of the said members and securing the latter together, spaced stops of cushioning material arranged in pairs and located in the path of the said extensions and 45 arranged to be engaged by the flanges thereof for limiting the rotative movement of the cupped members and for cushioning such movement, and means for connecting a chair seat with the said chair.

50 WALTER M. HANSON.
